CLAIM

The ornamental design for a rear view mirror as shown and described.

DESCRIPTION

FIG. 1 is a front perspective view of a rear view mirror showing my new design, which is mountable on the right side of a vehicle;

FIG. 2 is a rear perspective view thereof;

FIG. 3 is a front elevational view thereof;

FIG. 4 is a rear elevational view thereof;

FIG. 5 is a plan view from above thereof;

FIG. 6 is a plan view from below thereof;

FIG. 7 is a right side elevational view thereof;

FIG. 8 is a left side elevational view thereof;

FIG. 9 is a front perspective view of a rear view mirror showing a second embodiment of my new design, the sole difference being that it is mountable on the left side of a vehicle;

FIG. 10 is a rear perspective view of the embodiment of FIG. 9;

FIG. 11 is a front elevational view of the embodiment of FIG. 9;

FIG. 12 is a rear elevational view of the embodiment of FIG. 9;

FIG. 13 is a plan view from above of the embodiment of FIG. 9;

FIG. 14 is a plan view from below of the embodiment of FIG. 9;

FIG. 15 is a left side elevational view of the embodiment of FIG. 9;

FIG. 16 is a right side elevational view of the embodiment of FIG. 9
